UNITED STATES PATENT OFFICE

163,727

COMBINED PLANT RECEPTACLE AND SUPPORT

Bernard Yellin, Chicago, Ill.

Application April 6, 1951, Serial No. 14,725

Term of patent 7 years

(Cl. D35—3)

To all whom it may concern:

Be it known that I, Bernard Yellin, a citizen of the United States, and resident of Chicago, in the county of Cook, and State of Illinois, have invented a new, original, and ornamental Design for a Combined Plant Receptacle and Support, of which the following is a specification, reference being had to the accompanying drawing, forming a part thereof.

Fig. 1 is a front elevational view of a combined plant receptacle and support, showing my new design.

Fig. 2 is a top view of the same, with portions being shown in plan and other portions in section along the line 2—2 of Fig. 1.

The dominant features of my design reside in the portions shown in full lines.

The rear of the combined plant receptacle and support, that is, the side opposite to that shown in Fig. 1 is substantially identical in configuration to the illustrated side.

I claim:

The ornamental design for a combined plant receptacle and support, substantially as shown and described.

BERNARD YELLIN.
